US00D754659S

(12) **United States Design Patent**
Kim et al.(10) **Patent No.:** **US D754,659 S**
(45) **Date of Patent:** **** Apr. 26, 2016**(54) **INPUT DEVICE FOR AN ELECTRONIC TABLET**(71) Applicant: **Microsoft Corporation**, Redmond, WA (US)(72) Inventors: **Young Soo Kim**, Seattle, WA (US); **Mike F. Deily**, Redmond, WA (US); **James Iming Tsai**, Redmond, WA (US)(73) Assignee: **Microsoft Corporation**, Redmond, WA (US)(**) Term: **14 Years**(21) Appl. No.: **29/524,391**(22) Filed: **Apr. 20, 2015****Related U.S. Application Data**

(62) Division of application No. 29/467,600, filed on Sep. 20, 2013, now Pat. No. Des. 731,486.

(51) **LOC (10) Cl.** ..... **14-02**(52) **U.S. Cl.**USPC ..... **D14/392**(58) **Field of Classification Search**

Primary Examiner — Freda S Nunn(74) *Attorney, Agent, or Firm* — Banner & Witcoff, Ltd.(57) **CLAIM**

The ornamental design for an input device for an electronic tablet, as shown and described.

DESCRIPTION

FIG. 1 is a top isometric view of an input device for an electronic tablet showing the new design;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.
